(57) **CLAIM**

The ornamental design for a charger for implantable cardiac device, as shown and described.

DESCRIPTION

FIG. 1 is a perspective view of a charger for implantable cardiac device, showing our new design;

FIG. 2 is a rear view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The broken lines in the drawing illustrate portions of the charger for implantable cardiac device that form no part of the claimed design.

The oblique lines in the drawings indicate transparency.
